UNITED STATES PATENT OFFICE.

THOMAS JOHNSON, OF CHICAGO, ILLINOIS, ASSIGNOR TO HERMANN REND-TORFF, OF SAME PLACE.

DESIGN FOR SURFACE ORNAMENTATION OF STOVE-BOARDS.

SPECIFICATION forming part of Design No. 17,914, dated November 29, 1887.

Application filed November 3, 1887. Serial No. 254,926. Term of patent 14 years.

To all whom it may concern:

Be it known that I, THOMAS JOHNSON, a citizen of the United States, residing at Chicago, Illinois, have invented and produced a new Design for Surface Ornamentation of Stove-Boards, of which the following is a specification.

The surface of the board comprises an interior or central panel, A, surrounded by a border, B.

The surface of the panel A is clouded or mottled, having the general appearance given by what is known to the trade as "crystallized tin."

The border B presents a plain or unclouded surface, free from the ornamentation shown upon the central panel, and having the general appearance given by what is known as "tin," thereby forming a contrast.

I claim—

The design for surface ornamentation of a stove board herein shown, consisting of a clouded panel and a plain border surrounding the same, substantially as described.

THOMAS JOHNSON.
